UNITED STATES PATENT OFFICE.

AUGUSTINE R. AYERS, OF CLEVELAND, OHIO.

LOCOMOTIVE CONSTRUCTION.

Application filed April 7, 1924. Serial No. 704,866.

To all whom it may concern:

Be it known that I, AUGUSTINE R. AYERS, a citizen of the United States, residing at Cleveland, in the county of Cuyahoga and 5 State of Ohio, have invented certain new and useful Improvements in Locomotive Constructions, of which the following is a specification.

This invention relates to steam locomotives and particularly to locomotives equipped with feed water heaters located on top of the boiler either ahead or behind the stack.

In constructions of this general character 15 they are usually provided with pipes of comparatively large diameter extending upwardly from the steam chests to the heater, one pipe being usually arranged on each side of the smoke box. Because of the dis- 20 position of these pipes with respect to the remaining structure they obstruct the view of the engineman from the cab and furthermore make it extremely difficult to apply other pipes to the outside periphery of the 25 smoke box without causing said latter pipes to project outwardly a considerable distance. Aside from obstructing the enginemen's view these outwardly projecting pipes make difficult the passage of persons 30 back and forth on the running boards.

It is therefore the object of this invention to provide means whereby these pipes extending from the steam chests to the heater may be so arranged as not to incur the above 35 noted objections, this being rendered possible by providing recesses in the sides of the smoke box sufficiently deep to permit the aforesaid pipes to be housed therein, thus rendering the distance between the outsides 40 of these pipes substantially the same and in many instances less than the diameter of the smoke box.

This construction offers the further possibility of effectually protecting the pipes 45 from radiation as the arrangement permits of covering the pipes and also of disposing them in closer proximity to the heat of the smoke box itself. In addition the recesses in which these pipes are disposed are jacked- 50 eted thereby restoring the original contour of the smoke box and presenting a smooth sightly appearance.

The novel combination, construction and arrangement of parts constituting my im- 55 proved invention will be more apparent as this description proceeds, especially when

considered in connection with the accompanying drawings wherein:

Figure 1 is a fragmentary front elevation of a steam locomotive constructed in 60 accordance with my invention;

Fig. 2 is a fragmentary side elevation of the steam locomotive so constructed;

Fig. 3 is a fragmentary detail sectional view taken substantially on the plane indicated by line 3—3 of Fig. 2; and

Fig. 4 is a similar view of a modified form of construction.

Referring now particularly to the drawings wherein like reference characters indicate like parts it will be noted that only sufficient of the locomotive is shown in order to illustrate the application of the invention, there being shown in the drawings the steam chests 10, a feed water heater 11, a 70 smoke box 12, stack 13 and running boards 14. In steam locomotive constructions of this character it is customary to provide upwardly extending pipes connecting the steam chests 10 with the heater 11. Heretofore these pipes have been arranged adjacent the outside of the smoke box and have therefore constituted objectionable obstructions both to the view of the enginemen and to the passage of persons along the 75 running boards 14.

In carrying out my invention I contemplate providing vertically arranged recesses in which these pipes may be disposed throughout the greater part of their length. 80 These recesses may be produced in any one of a number of ways, for instance, as shown in Fig. 3 or Fig. 4 of the drawings. In Fig. 3 the wall 15 of the smoke box is shown as being cut away as at 16 to provide a vertically elongated opening therein. There is then attached to this opening a suitably shaped housing 17, this housing extending inwardly into the smoke box and being flanged as at 18 along its edges whereby it 85 may be suitably riveted or welded to the wall 15 of the smoke box.

There is thus produced on each side of the smoke box an open sided vertically extending recess, the diameter of which will be so selected as to freely receive the pipe 19 which connects the steam chests 10 to the heater 11. The space around the pipe 19 will then be preferably filled with some form of lagging or pipe covering 20. The open side of the recess is thereafter closed by means of a jacket or cover 21 whereby

the original contour of the smoke box is restored and a smooth and slight appearance produced.

In Fig. 4 a modified form of construction is illustrated and in this form of the invention it will be noted that the recess is produced by heating and forming the smoke box wall 15' in such a manner as to form a recess 22, the walls of which will be integral with 10 the wall 15 of the smoke box. The jacket or cover 21 will then be secured in place enclosing the recess and restoring the original contour of the smoke box. As in the preceding form the pipe 19 will preferably be 15 covered with a pipe covering of some character or the space within the recess filled with lagging or other material 20.

With the above described structures there is realized the advantage of eliminating the 20 obstructions arranged on the outer surface of the smoke box which are found objectionable for the reasons heretofore mentioned. In addition this construction offers the further possibility of effectually protecting the 25 pipe from radiation and heat dissipation, the contents of the pipe being on the other hand maintained in closer proximity to the heat of the smoke box than was heretofore possible.

30 While it is possible with this arrangement to dispose the pipe 19 partially within the smoke box still the pipes are separated therefrom by the walls 17 or 22 and the character of the construction is such that no specially 35 constructed fittings are necessary which in the case of leakage would prove disastrous to the steaming of the engine.

While the principle of this invention has 40 been described with reference to the pipes 19 extending from the steam chests to the heater still it will be immediately apparent that other of the pipes normally disposed on the outer surface of the boiler or smoke box may be advantageously disposed within the 45 walls of the boiler or smoke arch in the same manner as the pipes 19. Owing to the similarity of construction it is thought unnecessary in this present application to illustrate the invention as used in connection with 50 more than the pipes 19 but it should be nevertheless understood that this invention is not limited in this particular.

While one embodiment of the invention together with a slightly modified form of the 55 same have been illustrated herein in detail it should be understood that reservation is made to make such changes in the details of construction as may be deemed necessary and expedient and as may come within the 60 purview of the accompanying claims.

Having thus described my invention, what I claim is:

1. A locomotive construction including a steam chest, a feed water heater, a smoke box and a pipe connecting said steam chest 65 to said heater, said smoke box being formed with a recess adapted to receive said pipe.

2. In a steam locomotive structure of the character described including a steam chest, a feed water heater, a smoke box and a pipe 70 connecting said steam chest and feed water heater, said smoke box being provided with a recess adjacent one side thereof adapted to house said pipe, and a cover for closing the open side of said recess. 75

3. In a steam locomotive construction including steam chests, a feed water heater, a smoke box and pipes connecting said steam chests to said heater, vertically extending recesses formed in the sides of said smoke box 80 adapted to receive said pipes, and covers for closing the open sides of said recesses.

4. In a steam locomotive structure of the character described including steam chests, a smoke box, a heater arranged on top of 85 said smoke box and pipes extending upwardly from said steam chests and connecting with said heater, the side walls of said smoke box being provided with vertically extending passageways adapted to receive 90 said pipes, packing surrounding said pipes, and cover plates secured to said smoke box for closing the outer sides of said passageways. 95

5. In a locomotive construction, a plurality of steam chests, a smoke box, a feed water heater arranged on top of said smoke box, pipes extending upwardly from said steam chests to said heater, the walls of said smoke box being formed with vertically extending openings, housings secured to said smoke box along the edge of said openings and extending inwardly into said smoke box, said pipes extending through said housings, packing arranged in said housing and surrounding said pipe, and cover plates secured to said smoke box and covering the openings in said smoke box. 100 105

6. A locomotive construction including a boiler, a smoke arch and pipes extending 110 along said boiler and said smoke arch, said boiler or smoke arch being formed with recesses adapted to receive said pipes.

7. In a locomotive construction including a boiler, a smoke box and pipes extending 115 along the surface of said smoke box and boiler, said smoke box and boiler being provided with inwardly extending recesses adapted to enclose said pipes, and covers for closing the open sides of said recesses. 120

The foregoing specification signed at Cleveland, Ohio.

AUGUSTINE R. AYERS.
